UNITED STATES PATENT OFFICE.

SOL KAUFMAN, OF NEW YORK, N. Y., ASSIGNOR TO DAVID KLEBANOFF AND SAMUEL GROSSMAN, COPARTNERS TRADING UNDER THE FIRM NAME OF KLEBANOFF AND GROSSMAN, OF NEW YORK, N. Y.

DESIGN FOR A FINGER RING.

Application filed August 15, 1925. Serial No. 14,441. Term of patent 3½ years.

To all whom it may concern:

Be it known that I, SOL KAUFMAN, a citizen of the United States of America, residing at city, county, and State of New York, have invented a new, original, and ornamental Design for Finger Rings, of which the following is a specification, reference being had to the accompanying drawings, forming part thereof.

Fig. 1 is a top plan view of a ring embodying the new design.

Fig. 2 is a side elevation thereof; and Fig. 3 is an edge view thereof.

I claim:

The ornamental design for a finger ring as shown.

In witness whereof I have signed this specification this 14th day of August, 1925.

SOL KAUFMAN.
